[57] CLAIM

The ornamental design for safety spectacles, as shown
and described.

DESCRIPTION

FIG. 1 is a perspective view of the safety spectacles
showing my new design;

FIG. 2 is a front elevational view thereof;

FIG. 3 is a side elevational view thereof, the opposite
side being a mirror image;

FIG. 4 is a top plan view thereof;

FIG. 5 is a cross sectional view thereof;

FIG. 6 is a bottom plan view thereof.

FIGS. 4 and 6 are shown broken away for convenience
of illustration.

FIG. 1.FIG. 2.FIG. 3.FIG. 4.FIG. 5.FIG. 6.
